UNITED STATES PATENT OFFICE.

HEINRICH MEIER, OF UNTERAGERI, SWITZERLAND.

DRAWING MECHANISM.

Application filed January 29, 1926. Serial No. 84,624.

In order to permit working with considerable draftings in spinning mills and to save thereby labour, machines, power, space and so on without impairing the quality of the yarn, special drawing mechanisms must be utilized. These drawing mechanisms must be so constructed that the roving in the stretching zone is guided and held up to a point that is as close as possible to the pair of drawing rollers. The nearer this guidance is to the pair of drawing rollers the less powerful the clamping of the roving in the stretching zone must be as otherwise thickened parts in the rovings such as tufts or lumps are formed which are not permissible in the yarn.

Several types of such special drawing mechanisms or frames are on the market which tend to realize the above mentioned effect, for instance by means of pressure rollers made of a light metal, of wood or by pressure rollers having circumferential grooves. The first mentioned pressure rollers having a small weight are prevented from running when fly is deposited thereon; the grooves of the last mentioned rollers are easily damaged. With other systems which guide the rovings between leather bands up to the drawing rollers a perfect clamping action cannot be obtained; further these devices are very complicated, they must be carefully handled and must be attended to by skilled and reliable attendants.

It is the object of the present invention to provide a drawing mechanism for spinning machines which is simple, efficacious and cheap.

A constructional example of the subject matter of the present invention is illustrated on the accompanying drawings, in which:

Fig. 1 shows in a side elevation the drawing mechanism and

Fig. 2 is a plan view of Fig. 1 on a larger scale, and seen in the direction of the arrow A.

It may be assumed that the constructional example illustrated shows a drawing frame obtained by altering one of the known drawing mechanisms having a pair of feed rollers, a pair of drawing rollers and a pair of intermediate pressure rollers. The fluted lower rollers 1, 2 and 3 have not been altered and are mounted in the support consisting of the parts 4 and 5 of which the latter is adjustable relatively to the former in the

known manner. To the supporting part 5 an upper part 6 is hinged at 7 and in the part 6 the leather covered roller 8 is mounted; the latter and the roller 3 form together the pair of clamping rollers. The leather covered roller 9 which together with the lower roller 1 forms the pair of drawing rollers, is mounted in a bearing piece 10 adjustable along a rod 11 fixed to the part 6. The roller 9 is arranged nearer to the front than in the old drawing mechanism. The old pressure roller 12 is mounted in the bearing piece 13 having slots 14 in which the pins 15 of the pressure roller 12 are guided. An intermediate pressure or regulating roller 16 is provided to cooperate with the lower roller 2, with which also the roller 12 cooperates. The pins 17 of the roller 16 are guided in slots 18 of the bearing part 13.

The portions 19 of the roller 16 which bear on the rovings are reduced in diameter as compared with the remainder of roller 16. This reduction in diameter prevents the formation of tufts and lumps, as only the necessary braking effect is obtained and no excessive clamping, the weight of the roller 16 being principally supported by the lower roller 2. The yarn obtained thereby is very uniform and smooth.

The reduction in diameter of the intermediate pressure roller 16 must be in relation to the staple to be treated and to the yarn to be spun and the suitable reduction may be obtained in the following manner: Let it be assumed that Louisiana cotton of 28-30 millimetres staple is subjected to a twenty fold drafting for spinning a yarn of No. 30; the roving is then

$$\frac{30}{20} = 1.5 \text{ Engl.}$$

In this case the drawing mechanism is so adjusted that the distance from the clamping point of the rear pressure roller 12 and the middle lower roller 2 to the clamping point of the drawing rollers 1, 9 corresponds approximately to the longest fibres, i. e. to 30 millimetres. The front pressure or regulating roller 16 is so adjusted that its clamping point is at approximately 12 millimetres distance from the clamping point between the middle lower roller 2 and the intermediate roller 12. Roving No. 1.5 has a diameter of appr. 1.25 millimetres and yarn No. 30 has a diameter of appr. 0.25 millimetres. With the above stated adjustments and drafting

the diameter of the roving at the clamping point of the front pressure roller may be calculated to be

$$5 \quad \frac{1.25 + 0.25 \times 12}{2 \times 30} = 0.30$$

- millimetres. In order to regulate and uniformly distribute the fibres which are shorter than 30 millimetres the roller 16 must 10 press the roving so far that the diameter of the latter is reduced by one third. That is to say in the above mentioned case the radius of the pressure roller 16 must be reduced by 0.2 millimetres at the places where it cooperates with the rovings as compared with the other parts of the roller.

The regulating roller 16 may be made of a comparatively heavy material so that it does not get blocked by fly adhering to it 20 and in spite of its heavy weight it does not impair the drafting as the whole weight of the roller does not bear on the rovings and does not cause a clamping of the fibres.

I claim:

- 25 1. In a drawing mechanism, in combina-

tion, a pair of feed rollers, a pair of drawing rollers, a pair of intermediate pressure rollers, and a further intermediate pressure roller cooperating with the lower roller of said pair of intermediate pressure rollers, 30 the portions of said further pressure roller that bear upon the roving having a smaller diameter than the other portions of said pressure roller.

2. In a drawing mechanism, in combination, a pair of feed rollers, a pair of drawing rollers, a pair of intermediate pressure rollers, and a further intermediate pressure roller cooperating with the lower roller of said pair of intermediate pressure rollers, 35 40 the portions of said further pressure roller that bear upon the roving having a radius that is by two thirds of the thickness of the roving at the contacting point between said pressure roller and the cooperating lower 45 roller, smaller than the radius of the other portion of said pressure roller.

In testimony whereof, I have signed my name to this specification.

HEINRICH MEIER.
